DESIGN FOR A TOOL CABINET UNIT

William E. Greene, New York, N. Y.

Application February 15, 1937, Serial No. 67,669

Term of patent 14 years

To all whom it may concern:

Be it known that I, William E. Greene, a citizen of the United States and resident of New York city, in the county of New York and State of New York, have invented a new, original, and ornamental Design for a Tool Cabinet Unit, of which the following is a specification, reference being had to the accompanying drawing, forming a part thereof.

Fig. 1 is a perspective view of a tool cabinet unit, showing my new design, illustrated in closed position.

Fig. 2 is a similar view of the same in open position.

Fig. 3 is a plan view of Fig. 2.

I claim:

The ornamental design for a tool cabinet unit, as shown.

WILLIAM E. GREENE.
